UNITED STATES PATENT OFFICE.

CHARLES T. THOMPSON, OF PHILADELPHIA, PENNSYLVANIA.

SUPPORT FOR RODS.

1,227,020.

Specification of Letters Patent.

Patented May 22, 1917.

Application filed June 14, 1916. Serial No. 103,624.

To all whom it may concern:

Be it known that I, CHARLES T. THOMPSON, of Philadelphia, in the county of Philadelphia and State of Pennsylvania, have 5 invented certain new and useful Improvements in Supports for Rods, of which the following is a specification, reference being had to the accompanying drawings.

My invention relates to a support for rods, 10 such as curtain rods, and comprises a bracket piece pierced to receive the rod and an eccentrically rotating clamping ring associated therewith.

In the accompanying drawings Figure I, 15 illustrates a curtain rod with supports at each end embodying my invention.

Fig. II, is a sectional view of a support constructed according to my invention.

Figs. III, and IV, are side views of the 20 same, illustrating respectively the clamped and unclamped positions of the ring.

Referring to Fig. II, my invention comprises a base plate 1, attachable to the side of a door or sash by screws 2, and supporting a bracket 3, which is pierced by the 25 aperture 4, adapted to receive the curtain rod 5. Upon the side of the bracket 3, is formed the overhanging flange 6, which surrounds a ring piece 7, provided with a lug 30 8. The edge of the ring piece 7, is provided with a flange 9, which is received beneath and embraced by the overhanging flange of the bracket piece.

The ring piece 7, is pierced by an aperture 35 10, eccentrically related to the aperture 4, of the bracket (see Fig. IV). The eccentricity is such that when the ring piece is in the position shown in Fig. III, the rod 5, is freely received by both apertures, but when 40 the ring piece is rotated to position shown in Fig. IV, the eccentricity of the aperture of the ring causes the inner edge there-

of to bind the rod strongly against the opposing surface of the aperture 4. This binding or wedging action not only holds the 45 rod firmly against rattling, but keeps the ring piece from unintended rotation, so that the rod is at all times firmly secured in place.

Having thus described my invention, I 50 claim:

1. A support for a rod comprising a bracket piece provided with an aperture adapted to receive the rod, and a rotating clamping ring eccentrically associated with the aperture of the bracket piece. 55

2. A support for a curtain rod comprising an apertured bracket adapted to engage the rod to be supported, a ring piece also adapted to engage said rod, coöperating flanges upon the bracket and ring piece, 60 whereby the ring piece is rotatably secured in relation to the bracket, and an aperture in the ring piece eccentrically related to that of the bracket, whereby a binding action is secured on said rod by the rotation of the 65 ring piece.

3. A support for a rod, comprising a fixed member, having an aperture adapted to engage the rod to be supported; a rotary member concentrically mounted on said 70 fixed member, and also having an aperture adapted to engage said rod, but said aperture being in eccentric relation to the first mentioned aperture, whereby a binding action is secured on the rod by the rotation of 75 said rotatable member.

In testimony whereof, I have hereunto signed my name at Philadelphia, Pennsylvania, this sixth day of June, 1916.

CHARLES T. THOMPSON.
